SPINNING REEL

John K. Taggart, Indianapolis, Ind., Philip M. Parker, Rogers, Ark., and Earl E. Miller, Dowagiac, Mich., assignors to James Heddon's, Sons, Dowagiac, Mich., a corporation of Michigan

Filed Nov. 4, 1965, Ser. No. 87,995

Term of patent 14 years

(Cl. D31—4)

FIGURE 1 is an elevated perspective view of a spinning reel embodying our new design;

FIGURE 2 is a side elevational view thereof;

FIGURE 3 is a front end elevational view thereof;

FIGURE 4 is a rear end elevational view thereof;

FIGURE 5 is a top plan view thereof;

FIGURE 6 is a side elevational view of the opposite side of our new design from that shown in FIGURE 2; and

FIGURE 7 is a bottom plan view thereof.

We claim:

The ornamental design for a spinning reel, as shown.
